PAPER FASTENER

Jaime D. Cayabyab, Binalonan, Pangasinan,
Philippines

Application May 8, 1947, Serial No. 746,727

3 Claims. (Cl. 24—153)

1

My invention relates to new and useful improvements in paper fastening devices.

An important object of my invention is the provision of a paper fastener that is easily adjustable to accommodate various sizes of paper having standard punchings.

Another object of my invention is the provision of a device of the above mentioned character that includes upstanding prongs which extend through the punchings in the paper and wherein the construction is unique in that prongs of any desired capacity may be interchangeably used.

Still another object of my invention is the provision of a device of the above mentioned character that is simple in construction, inexpensive to manufacture and efficient and efficacious in the performance of its duties.

Other objects and advantages of my invention will be apparent during the course of the following description.

In the drawings, forming a part of this specification, and wherein like numerals are employed to designate like parts throughout the same,

Figure 1 is a perspective view of my paper fastener and illustrating the slidable cover thereof in a closed and locked position holding several sheets of paper or the like together,

Figure 2 is a view similar to Figure 1 but illustrating the cover in the open position,

Figure 3 is a broken perspective view of the sliding cover embodying a part of my invention,

Figure 4 is a broken perspective view of the compressor strip embodying a part of my invention,

Figure 5 is a broken perspective view of the base plate and the removable prongs associated therewith,

Figure 6 is a fragmentary perspective view taken on the line 6—6 of Figure 5,

Figure 6a is a transverse sectional view taken on line 6a—6a of Figure 5,

Figure 7 is a transverse sectional view taken on the line 7—7 of Figure 1,

Figure 8 is a transverse vertical sectional view taken on the line 8—8 of Figure 2,

Figure 9 is a transverse vertical sectional view taken on the line 9—9 of Figure 1,

Figure 10 is a transverse vertical sectional view taken on line 10—10 of Figure 1,

Figure 11 is an enlarged fragmentary transverse sectional view similar to the view illustrated in Figure 8 but showing in greater detail the manner in which the cover and compressor strip interlock to prevent complete removal of the

2

cover when the same is moved to the open position illustrated in Figure 2.

Figure 12 is a perspective view of a modified form of the invention,

Figure 13 is a view similar to Figure 12 but showing the cover in the open position,

Figure 14 is a perspective view of the base plate and the removable prongs used in the form of the invention illustrated in Figure 12,

Figure 15 is a perspective view of a modified form of the invention as illustrated in Figure 12, the sliding cover being here illustrated as being both slidably and hingedly associated with the compressor strip and the cover being here illustrated as in the unlocked and open position,

Figure 16 is a perspective view of a modified construction of the base and detachable prongs illustrated in Figure 14,

Figure 17 is a perspective view illustrating still another modification of the base plate and upstanding prongs,

Figure 18 is a transverse vertical sectional view taken on the line 18—18 of Figure 12,

Figure 19 is a fragmentary longitudinal vertical sectional view taken on the line 19—19 of Figure 17,

Figure 20 is a fragmentary perspective view illustrating yet another modification of the base and upstanding prongs, and

Figure 21 is a fragmentary longitudinal vertical sectional view taken on the line 21—21 of Figure 20.

In the accompanying drawings, wherein for the purpose of illustration, is shown a preferred embodiment of my invention the numerals 25,

26 and 27 designate a base plate, a compressor strip and a cover respectively, each of which part is preferably formed from a relatively thin sheet of a suitable metallic material. The base plate 25 carries upstanding prongs or tongues

which are removably associated therewith and adjustable relative thereto to accommodate various sizes of paper having standard punchings. The base plate is arranged below the stack of paper 29 and the upstanding prongs or tongues

28 project through the openings in the paper and through the transverse slots 30 provided in the compressor strip 26 mounted on top of the stack of paper 29 and directly above the base plate. The portion of the prongs 28 projecting above the compressor strip are folded in the direction of each other and against the top surface of the compressor strip in the manner best illustrated in Figure 2, and the cover 27 is slidably moved

from the open position illustrated in Figure 2 to hold the closed position illustrated in Figure 1 to hold

the prongs in the folded position whereby to prevent the same from opening and releasing the paper 29 and whereby to present a neat and pleasing appearance.

As best illustrated in Figure 5, the base plate 25 has the front and rear marginal edges or flanges 30 and 31 thereof bent upwardly and back upon themselves, which reversely bent portions are spaced slightly above the intermediate portion of the plate to provide guideways 32 and 33 in which the edges of the prong bases 34 are slidably disposed. As clearly illustrated in the drawings, the bases of the prongs are disposed at right angles thereto and are substantially wider than the prongs. The prongs are slidably applied to the base through the open ends thereof and the portions of the base projecting laterally of the prongs engage under the overhanging marginal edges 30 and 31 of the base to normally hold the same securely but detachably associated therewith. The prongs are of a width slightly less than the distance between the terminal edges of the overhanging portions 30 and 31 of the base and they project vertically therefrom and through the punchings in the paper 29. As is well known, paper of various sizes is provided with various standard punchings and I have therefore provided the base with lugs or stops 35 which locate the tongues in a position to fit the various standard punchings. In the interest of strength and economy of construction, I have here illustrated the stops as comprising tabs formed integrally on the terminal edges of the reflexed portions 30 and 31 of the base. It is to be noted that the tabs 35 are integral on the inturned edges 30 and 31, and are bent downwardly and then inwardly, Figures 5, 6 and 6a. The inner ends of the tabs 35 form a clearance 35b with the base plate. Also, the prong base 34 is provided with turned up ends 34b slidably engaged in the guideways 32 and 33, the tabs 35 being separated from each other by a clearance 35a. On the prong base is an integral tongue or tab 34a. This projection is arranged at the opposite end of the base remote from the prong and is folded over the tabs 35 when the connection of the prong base 34 has been made therewith in order to retain the prong against displacement relative to the base plate 25. Also, the prong 23 when in its bent up position will engage the opposite ends of the tabs. To remove the prong base, the tab 34a is merely unfolded and then the base can be slid out from under the tabs or stops 35. By having the tabs 35 bent downwardly, as well as inwardly, there is provided a recess over the ends of the tabs into which the tab 34a can be disposed.

As hereinabove described the prongs project through the punchings in the paper and the portions extending above the paper are received within the slots 30' formed in the compressor strip 26. The front and rear marginal edges of the compressor strip 26 are provided with integral hollow arcuately reflexed portions 36 and 37 which form guideways for the sliding cover 27. The reflexed portions 36 and 37 are co-extensive with the length of the plate and the terminal edges of these portions are spaced from the upper surface of the plate to accommodate the cover as illustrated in Figure 7. However, at the end 38 of the plate 26 the reflexed portions are formed with inturned lips 39 and 40 respectively, which lips form abutments adapted to prevent the cover from being entirely removed from the compressor strip.

The cover 27 is formed with an arched medial

portion 41 to accommodate the folded portions of the prongs 23 and the front and rear marginal edges thereof are rolled upwardly and back upon themselves to provide guides and these guides are of a size adapted to be snugly but slidably received within the guideways 42 and 43 provided by the arcuately reflexed front and rear marginal edges of the compressor strip 26. As best illustrated in Figure 3 the terminal edges 44 and 45 of the cover 27 are spaced substantially above the top surface of the cover for substantially their entire length whereby to extend above the inturned lips 39 and 40 formed at the end 38 of the compressor strip as best illustrated in Figure 9. However, the end 46 of the cover 27, which is the end remote from the end 38 of the compressor strip, is provided with interlocking means which engage with the inturned lips 39 and 40 of the compressor strip to prevent the cover from being entirely removed therefrom. The interlocking means comprises integral lips 47 and 48 formed on the reversely bent front and rear terminal edges of the cover which lips extend downwardly and terminate in proximity to the upper surface of the cover in a manner to extend transversely of and below the inturned lips 39 and 40 of the compressor strip as best illustrated in Figure 11 of the drawings. Attention is again directed to the fact that the integral lips 39 and 40 of the compressor strip and the lips 47 and 48 of the cover are disposed at opposite ends thereof and it is noted at this point that the respective lips extend for only a short distance along the length of the compressor strip and cover.

When the cover 27 is applied to the compressor strip 26 the end 49 thereof is positioned at the end 50 of the compressor strip 26 and the reversely curved marginal edges 44 and 45 thereof are fitted within the guideways 42 and 43 of the compressor strip 26. The cover 27 is telescoped within the compressor strip 26 until the end 49 thereof is moved to a position coincident with the end 38 of the compressor strip 26 and in view of the fact that the cover and compressor strip are co-extensive the cover will, at this time, entirely close the compressor strip. After the cover has been moved to this position the flap 51 formed integrally at the end 50 of the compressor strip is bent upwardly and as clearly illustrated in Figure 4 the outer edge of this flap is shaped to coincide with the upper profile of the compressor strip in a manner whereby it will close the end of the guideways 42 and 43 and also the end of the cover. The opposite end of the compressor strip is also formed with an upstanding flange 52 which closes the corresponding end of the cover but does not prevent sliding movement of the cover across the flange. If it is now desired to move the cover to the open position illustrated in Figure 2 it is moved by finger pressure in the direction of the flange 52. By reason of the fact that the terminal edges 44 and 45 of the cover terminate substantially above the upper surface thereof and above the inturned lips 39 and 40 of the compressor strip sliding movement of the cover may be easily effected. The cover may be slidably actuated in this manner until the inner edges of the downwardly extending lips 47 and 48 thereof abuttingly engage the inturned lips 39 and 40 of the compressor strip, as best illustrated in Figure 11, at which time the cover will be securely held against further sliding movement in the direction of the arrow in Figure 1. As illustrated in Figure 2, however,

the cover when in this position will permit the prongs 28 to be raised whereby to permit the compressor strip and cover, as a unit, to be moved so that a portion of the paper 29 may be removed or additional sheets thereof may be placed thereon. When the compressor strip is replaced and the prongs are again moved to the folded position the cover may be reversely shifted to bring the end 46 thereof into abutting engagement with the flap 51 of the compressor strip whereby to hold the prongs in the folded position and to present a neat and attractive appearance.

Attention is now directed to Figures 12, 13 and 14 which illustrate a modification of the above described form of the invention. This form of the invention is of a size adapted to accommodate the larger sizes of paper. The main differences reside in the manner in which the base plate is formed, the compressor strip and cover being formed and associated in the manner hereinabove described. Obviously, when the device is to be used in association with larger sizes of paper it will be necessary that the base be substantially longer in order that it may extend for substantially the entire length of the paper. The reflexed marginal edges 30 and 31 of the base 25 are provided with recesses 55 which permit the intermediate prongs 28 to be fitted to the base. The base plate is provided with stops 35 in the manner hereinabove described to properly locate the prongs and the endmost prongs are inserted through the open ends of the base plate and the intermediate prongs are inserted through the recesses 55. As best illustrated in Figure 14, the prongs are arranged in longitudinally spaced pairs and the stops locate the prongs of each pair to properly receive the punchings of the paper. The advantage realized by providing a longer base 14 is that the paper is compressed for substantially its entire length whereby to prevent the same from buckling and tearing at the unsupported portion thereof between the fasteners if two of the relatively short fasteners illustrated in Figures 1 through 11 were used.

If the device is to be used in connection with paper not provided with standard punchings a base constructed in the manner illustrated in Figure 16 may be advantageously used. In this form of the invention the endmost prongs 28 are located by stops 35 and the intermediate prongs are freely slideable in the guideways 32 and 33 for substantially the entire distance between the endmost prongs. The reflexed marginal edges 30 and 31 of the base are provided with confronting recesses 55 which accommodate the bases of the intermediate prongs and permit the same to be inserted within the guideways. The intermediate prongs may then be adjusted relative to a respective one of the endmost prongs and may thus be spaced a distance therefrom best suited to the exigency of the particular situation.

In Figures 17 and 19 I have illustrated a further modification of the base 25 which provides a construction wherein the ends of the base are closed by upstanding flanges 56. In practice, the bases of the endmost flanges are fitted into the guideways 32 and 33 through the recesses 55 formed in the reflexed marginal edges 30 and 31 intermediate their ends. The bases extend from the upstanding portions of the prongs in the direction of the respective ends of the base and are normally positioned in abutting engage-

ment with the upstanding flanges 56. The intermediate prongs may be fitted into the guideways through the recesses 55 and spaced any selected distance from a respective one of the end prongs.

In Figures 20 and 21 I have illustrated a further modification of the form of the invention illustrated in Figures 17 and 19. In this form of the invention the endmost prongs 28 are located in substantially spaced relation from the end of the base by means of the stops 35. This construction permits the base to extend substantially beyond the endmost prongs and to thereby provide additional support for the portion of the paper extending between the punchings and the upper and lower edges of the sheets.

In Figure 15 I have illustrated a modification of the invention. I have illustrated the cover 27 as being both slidably and hingedly associated with the compressor strip 26. To accomplish this purpose, I have provided the reflexed front portion 36 of the compressor strip with a plurality of longitudinally spaced recesses 57. The reflexed front marginal edge of the cover is similarly provided with recesses 58. When the cover is disposed in the closed position illustrated in Figure 12 the portions of the front reflexed marginal edge of the cover will be fitted within the guideway 42 provided by the reflexed front marginal edge of the compressor strip. If, however, the cover is shifted a slight distance toward the open position the portion of the reflexed front marginal edge of the cover extending between the recesses 58 will move into register with the recesses 57 in the reflexed front marginal edge of the compressor strip. The recesses 57 are uniquely formed to properly accommodate the mentioned portion of the cover and to permit the same to be lifted vertically whereby to permit the cover to be swung upwardly to the open position illustrated in the drawing. Attention is directed to the fact that the reflexed rear marginal edge of the cover is provided with a substantially centrally located recess 59 which determines the extent to which the cover may be slidably moved relative to the compressor strip. The reflexed rear marginal edge of the compressor strip is crimped as at 60, which crimped portion is normally disposed in proximity to the end 61 of the recess 59 when the cover is in the closed position. The cover may therefore be shifted longitudinally of the compressor strip until the end 62 of the recess engages the crimped portion 60 at which time further shifting of the cover is prevented. The crimped portion of the compressor strip therefore prevents the cover from being entirely removed from the compressor strip and holds the same adjustably but fixedly associated with each other. It is to be realized, however, that in any event the distance which the cover is permitted to be moved relative to the compressor strip is sufficient to permit the reflexed front marginal edge of the cover to be moved into register with the recesses 57 in the reflexed front marginal edge of the compressor strip.

I have found that if the cover is formed with a knurled portion 63 the sliding of the cover is substantially expedited. The knurled portion properly locates the finger of the operator free from contact with the stationary edges of the compressor strip and prevents the finger from slipping when lateral pressure is exerted against the cover.

It is to be understood that the forms of my

invention herewith shown and described are to be taken as preferred examples of the same and that various changes in the size, shape and arrangement of parts may be resorted to without departing from the spirit of my invention nor the scope of the subjoined claims.

Having thus described my invention, I claim:

1. In a paper fastener, the combination which comprises an elongated base strip having in-turned longitudinally disposed flanges with spaced lugs extended from the inner edges of the flanges and with the flanges positioned on the longitudinally positioned edges of the strip, and vertically disposed tongues having horizontally disposed bases with extended flanges at the edges of the bases and said flanges being offset upwardly for frictional engagement with the flanges of the base strip.
2. In a paper fastener, the combination which comprises an elongated base strip having in-turned longitudinally disposed flanges with spaced lugs extended from the inner edges of the flanges and with the flanges positioned on the longitudinally positioned edges of the strip, vertically disposed tongues having horizontally disposed bases with extended flanges at the edges of the bases and said flanges being offset upwardly for frictional engagement with the flanges of the base strip, and horizontally disposed tongues on the edges of the bases extended over the lugs of the flanges of the base strip for securing the said vertically disposed tongues in position on the said base strip.
3. In a paper fastener, the combination which comprises an elongated base strip having in-

5

turned longitudinally disposed flanges with spaced lugs extended from the inner edges of the flanges and with the flanges positioned on the longitudinally positioned edges of the strip, vertically disposed tongues having horizontally disposed bases with extended flanges at the edges of the bases and said flanges being offset upwardly for frictional engagement with the flanges of the base strip, and horizontally disposed tongues on the edges of the bases extended over the lugs of the flanges of the base strip for securing the said vertically disposed tongues in position on the said base strip, said fastener adapted for use with a compression strip having rolled flanges at the edges and having transversely disposed slots therein with the slots positioned to receive the vertically disposed tongues of the said bases, a cover strip also having rolled flanges on the edges positioned to slide into and frictionally engage the flanges of the said compression strip, and extensions providing stops at the ends of the said compression strip for limiting longitudinal travel of the parts.
